WILLIAM S. PORTER, OF BOSTON, MASSACHUSETTS.

Letters Patent No. 84,902, dated December 15, 1868.

IMPROVEMENT IN BUTTON-HOLE CUTTERS.

The Schedule referred to in these Letters Patent and making part of the same.

To all to whom these presents shall come:

Be it known that I, WILLIAM S. PORTER, of Boston, in the county of Suffolk, and State of Massachusetts, have made an invention of a new and useful or improved Button-Hole Cutter; and do hereby declare the following to be a full, clear, and exact description thereof, due reference being had to the accompanying drawings, making part of this specification, and in which—

Figure 1 is a side elevation,

Figure 2, a longitudinal section, and

Figure 3, a vertical and transverse section of my invention.

This invention relates to means for not only cutting a button-hole in any description of material in a smooth and perfect manner, but for adjusting, by an expeditious and easy plan, the length of cut or button-hole made by the instrument; the invention further relating to means for regulating the distance of the button-hole from the edge of the cloth or other material in which the incision is made.

The invention consists in the employment of two jaws, pivoted together, and moving toward and from each other in a vertical plane, one of such jaws being provided with a pointed cutter, and the opposite jaw with a slot or passage for receiving such cutter, substantially as hereinafter described.

The invention further consists in applying, in a movable manner, to the inner face of the shank of one of the jaws, a stop or abutment, the position of which thereon is fixed relatively to the cutter by a set-screw, to enable its position to be readily adjusted.

In the drawings above mentioned, A A denote two jaws, as composed respectively of a flat and somewhat extended head, *a* or *a'*, and a short shank, *b* or *b'*, these shanks being pivoted together, as shown at *c*, and extended beyond such pivots into handles *d d*, after the manner of ordinary scissors.

The heads *a a'* are recessed or slotted through their greatest area, as shown at *e e*, and into one of these recesses or incisions a triangular and slightly-hooking knife, *f*, or cutter, is inserted, the point of such knife extending toward the opposite jaw, and, when such jaws are partially or wholly closed, is secured within the incision of such jaw.

The knife *f* is retained within its recess by a clamp-screw, *g*, made through the head *a*, as represented, the head of the screw overlapping the boundaries of this slot, and serving, by pressure thereupon, to retain the knife firmly in any desired position with respect to the

opposite jaw, the inner edge of this knife being substantially a circle, struck from the fulcrum of the jaws A A.

h, in the drawings, denotes a stop or abutment, applied to the inner face of one of the shanks *b* or *b'*, and being of such a size as to retain the inner faces of the heads *a* or *a'* about parallel to each other.

The said stop or abutment *h* is retained in place upon the shank by a clamp-screw, *i*, which extends through a slot, *j*, made in such shank.

The mode of using the above-described implement will at once manifest itself to intelligent persons.

The cloth or other material is held in the left hand, and passed between the jaws A A until its edge comes in contact with the stop *h*, the handles *d d* being held in the operator's right hand, and brought together in the same manner as with an ordinary scissors, which has the effect of forcing the jaws A A toward one another, and driving the knife through the material and cutting the button-hole, the length of this button-hole being dependent on the portion protruding beyond its jaw.

From the above description it will be seen that it is only necessary to advance or retract the knife, with respect to the edge of the jaw containing it, to form a button-hole of any desired length, and to insure an equality and uniformity of length of a number of button-holes cut by the implement.

The stop *h* also serves a very useful purpose in varying the distance of the button-hole from the edge of the material in which it is cut.

The peculiar shape, as well as relative position of the knife, enables it to make a drawing-stroke and smooth cut, and to be forced through the material with the exertion of very little power from a person's hand.

1. I claim the combination and arrangement, with the jaws A and stop *h*, of the knife *f*, held in one of said jaws, and made adjustable, so as to project a greater or less distance therefrom, in the manner and for the purposes set forth.

2. Also, providing the jaws A with slotted or recessed heads *a a'*, constructed and arranged, with relation to each other and the knife *f*, substantially as and for the purposes shown and specified.

WM. S. PORTER.
